UNITED STATES PATENT OFFICE.

CHARLES H. SALISBURY AND SIDNEY M. STEVENS, OF DE KALB, ILLINOIS.

WIRE-FENCE STRETCHER.

SPECIFICATION forming part of Letters Patent No. 237,412, dated February 8, 1881.

Application filed September 29, 1880. (Model.)

To all whom it may concern:

Be it known that we, CHARLES H. SALISBURY and SIDNEY M. STEVENS, of De Kalb, in the county of De Kalb and State of Illinois, have invented new and useful Improvements in Wire-Fence Stretchers and Hoisting-Tackle, of which the following is a specification.

This invention relates to a stretcher intended primarily for use in straining fence-wires. Its object is to simplify and lighten the structure; and to this end it consists in the peculiarities of construction hereinafter detailed.

In the accompanying drawings, Figure 1 is a perspective view of the apparatus as it appears in use. Fig. 2 is an enlarged perspective of the rope-hook. Fig. 3 is a horizontal section of the device.

We make the windlass A and its journals of one piece of cast metal, for the sake of cheapness. This renders necessary the making of the stretcher-frame, which is also of metal, in two parts—that is to say, one of the arms or ends of the frame, embodying one of the windlass-bearings, must be made separate from the balance of the frame in order to permit the windlass to be inserted in its bearings. Therefore one of the sides B of the frame is formed of an independent piece of metal, having formed therein an arbor for the windlass, and it is united to the cross-head C, which it laps over, by rivets c upon one part passing through corresponding openings in the other part. This permits the putting together of the frame after the windlass has been put in its bearings by uniting the parts B and C, as shown, a firm union being accomplished by flattening the heads of the rivets.

It is also desirable, though not necessary, to make the side B' separate and secure it to the cross-head in like manner, as it is a duplicate of the side B, except that it bears a pivot, d, for the weighted pawl D, which engages a ratchet, e, on the arbor of the windlass-crank E to prevent unwinding of the windlass. This pawl is secured upon said pivot by merely flattening the outer end of the latter. The

crank E is secured upon the squared end of the windlass-journal by hammering the lip m upon the former down into a recess, o, provided in one of the angles or sides of the latter.

Upon the cross-head C is a dog, I, for taking hold of the end of the wire, as shown, and upon the end of the rope G a hook, H, for securing the latter around the post. Upon the hook H is another dog, I', for use when it is desired to bring the ends of the fence-wire together for splicing. By combining the dog with the piece upon which the hook is formed a saving of weight and in the number of parts is effected.

Our invention is very cheap because of its reduced weight (being but a fraction of the weight of those in ordinary use) and the ease with which it is made and put together, none of the parts requiring any preparatory finishing. It is so light and small that it can be carried in the pocket with perfect ease.

We claim—

1. As a new manufacture, a wire-fence stretcher consisting of a windlass and its journals, all made in one piece of metal, and a metal frame whereof one side, embodying one of the windlass-arbors, is made separate from the other part of the frame, so as to permit the insertion of the windlass, and is permanently riveted to said other part after such insertion, substantially as specified.

2. The stretcher provided with a windlass the squared end whereof is provided with a recess, o, and, in combination with such squared end, a crank having a lip, m, located with reference to the recess so as to be hammered down into the same, substantially as specified.

3. The combination, with the stretcher, of the rope, the hook H, and the dog I', both the latter being upon one piece, substantially as set forth.

CHARLES H. SALISBURY.
SIDNEY M. STEVENS.
